UNITED STATES PATENT OFFICE.

HARRY BROCK AND JACOB DAUTCH, OF BUFFALO, NEW YORK.

SHOE STRETCHER.

Application filed May 17, 1926. Serial No. 109,589.

This invention relates to means for stretching shoes and has for its object the provision of a novel device adapted to be inserted within a shoe of any kind and any size, within 5 certain reasonable limits, and provided with means whereby the shoe may be stretched laterally or longitudinally in case such is found necessary for the convenience and comfort of the wearer.

An important object is the provision of a single device which may be operated either for stretching shoes laterally or longitudinally, it being consequently unnecessary to have two separate mechanisms for performing the different operations, there being, as a result, a saving in the cost of equipment and also a reduction in the length of time necessary to stretch or strain a shoe.

A further object of the invention is the provision of a device of this character and for this purpose embodying novel operating means for effecting lateral expansion to stretch a shoe transversely, the same operating means being capable of actuation to expand the device longitudinally for effecting longitudinal stretching.

Another object of the invention is to provide a shoe stretcher embodying wing elements having a peculiar pivotal mounting 30 and adapted to be forced apart by a specially arranged cam structure to exert the desired stretching action upon a shoe, peculiarly constructed and mounted spring means being provided for normally urging the wing members into contracted relation.

A more specific object is to provide a stretching or straining device which in addition to the pivoted wing elements includes a heel engaging element movably mounted with 40 respect to the body, a floating or longitudinally movable screw element being provided for selectively operating the wing elements or the heel engaging member.

The invention further contemplates the provision of a mechanism of this character embodying various structural features which will be of manifest advantage, the device being moreover simple and inexpensive to manufacture, easy to assemble and use, positive in action, efficient and durable in service, and a general improvement in the art.

With the above and other objects and advantages in view, the invention consists in the details of construction and arrangement of 55 parts to be hereinafter more fully described

and claimed, and illustrated in the accompanying drawings in which:

Figure 1 is a perspective view of the complete device, the initial or contracted position being shown by full lines and the expanded position being illustrated by dotted lines, 60

Figure 2 is a central vertical longitudinal section through the device,

Figure 3 is a vertical cross sectional view 65 taken on the line 3—3 of Figure 2 and looking in the direction of the arrows,

Figure 4 is a horizontal longitudinal section through the device taken on the line 4—4 of Figure 2 and looking in the direction of 70 the arrows,

Figure 5 is a cross sectional view through the forward portion of the device taken on the line 5—5 of Figure 1 and illustrating the spring means connected with the wing members, 75

Figure 6 is a fragmentary detail sectional view taken on the line 6—6 of Figure 1 and illustrating the mounting of the heel engaging member, and

Figure 7 is a detail sectional view taken on the line 7—7 of Figure 4 and showing the pivotal mounting for the wing members.

Referring more particularly to the drawings, we have shown the device as comprising 85 a body member 10 of suitable size, shape and material and formed with a forwardly extending shank 12 terminating in a widened portion 13 adapted to be engaged within the toe portion of a shoe, slipper, boot or other 90 article of footwear to be stretched. The body member 10 is of course intended to be located to the rear of the center of the shoe and carried at the rear side thereof, by means to be described, is a block-like member 14 adapted to engage within the heel portion of 95 the shoe. At the juncture of the body portion 10 with the shank portion 12 are shoulders 15 upon which may be formed forwardly extending trunnion elements 16 which terminate short of the upper ends of 100 the shoulders as clearly indicated in Figure 7. Actually, the various parts may conveniently be formed as aluminum castings in which event these trunnion elements would 105 of course be integral with the body member 10.

The numeral 17 designates a pair of wing members which are located at opposite sides of the shank 12 and which are formed at 110

their rear ends with bearing sockets 18 rotatably engaged upon the trunnions 16 so that the wing members will be capable of lateral movement toward or from each other. These wing members are curved in shape so as to conform substantially to the curvature of the sides of a shoe. The shoulders 19 at the rear of the toe piece 13 are beveled off as indicated so as not to 10 interfere with the swinging movement of the wings under the influence of means to be described.

It is preferable that the entire device including the body, the heel engaging member 15 and the wings, together with the toe piece, be shaped to conform, more or less, to the shape of a shoe, the bottom surface being curved in conformity with the usual shape at the sole, and the other surfaces also 20 being curved in substantially the manner disclosed, there being, however, no particular limitations in this respect as many variations may be resorted to.

The shank member 12 is formed with a 25 longitudinally extending slot 20 and the confronting sides of the wing members 17 are formed with grooves 21 opposite the slot, the grooves terminating short of the ends of the wing members and the forward ends 30 thereof being curved as shown at 22 for co-operation with a cam head 23 on the forward end of a floating operating screw 24 which is mounted for longitudinal movement with respect to the device and which is 35 slidable through a bore 25 in the body 10 and operated by means to be described. The wings are normally held together or in retracted position as by means of a coil spring 26 here shown as extending through a transverse hole 27 in the shank 12 and through registering holes 28 in the wing members, the ends of the spring being connected with screws 29, or their equivalent, countersunk within the opposite sides of the wing members. Clearly, at least one of the screws 29 45 must be detachably connected with the spring in order that assembling may be effected.

The heel engaging member 14 above 50 described is shown as guidably connected with the body 10 as by means of a plurality of tubular elements 30 preferably screwed into tapped holes 31 in the member 14 and slideable within bores 32 in the body 10. The 55 end of each tubular element engaged with the member 14 is represented as counter-bored at 33 to define a retaining shoulder 34 for the head 35 of an anchor member which includes an extension 36 to which is suitably 60 secured a coil spring 37 located within the tubular element and connected with a screw or the like 38 countersunk in the body 10 at the shoulder portion 15 thereof. The spring 37 in all of the tubular guide members 65 operate to hold the heel engaging mem-

ber 14 normally retracted or in engagement with the rear end of the body. While there are four of these tubular guide elements disclosed, it should be understood that the number may be increased or decreased without materially affecting the invention and it is also possible to provide other specific spring means instead of what is illustrated, if found advisable.

Journalized through the top of the body 10 75 is an operating shaft 39 carrying a suitable handle such as that illustrated at 40 whereby it may be rotated. Carried by the lower end of this shaft and located within a recess or chamber 41 in the body is a bevel gear 42 meshing with a bevel gear 43 threaded onto the screw 24 and having a hub portion 44 engaging within a recess 45 in the body so that the gear cannot shift out of its operative position.

The initial position of the parts is illustrated by full lines in Figure 1 of the drawings. In the operation it will be seen that if it is desired to stretch a shoe transversely, the device is inserted therein, subsequently to which the operator turns the handle 40 in the proper direction to rotate the gear 43 in such direction that it will act to move the screw 24 forwardly. As a matter of fact it may be preferable to provide this screw with a left hand thread so that the natural tendency of the operator to turn the handle to the right will result in forward movement of the screw. When the screw is moved forwardly the cam head 23 on the forward end thereof slides along the grooves 21 and when the convex forward portion of this head approaches or contacts with the curved forward ends 22 of the grooves the wing members 17 will be swung apart as indicated by dotted lines in Figure 1, thus exerting a stretching or straining action upon the shoe.

After a shoe has been stretched transversely and it is desired to stretch it longitudinally, or if it is desired to perform the latter operation irrespective of the former, the device is placed within a shoe and the handle 40 turned in the other direction, in the present instance, counter-clockwise. The rotation of the gears will then cause the screw 24 to be moved rearwardly, the head 23 sliding along the grooves 21. After a few turns of the handle, the rear end of the screw will abut against the inner face of the heel engaging member 14 and continued turning movement of the handle will result in the member 14 being forced away from the body for effecting the desired stretching action. The tubular members 30 act to guide the member 14 in its movement and to prevent canting or other distortion effects. Of course the springs 37 will hold the member 14 in engagement with the screw 24 and will act to restore the member to its initial position when the handle is turned in the 130

opposite direction at the termination of the stretching action. It is clear that the screw 24 may be said to be floating inasmuch as it travels longitudinally under the influence of 5 the gearing driven by the operating handle. The engagement of the head 23 within the grooves 21 prevents turning of the screw and restricts its movement to the longitudinal.

From the foregoing description and a 10 study of the drawings it will be apparent that we have thus provided a very simply constructed and easily operated device for the purpose of stretching shoes. A great advantage is that both longitudinal and 15 transverse stretching may be effected by the employment of this single device it being unnecessary for the shoe dealer or other person to have separate devices for the two different operations. This results in not only a saving 20 in the cost of the equipment but also a reduction in the time involved inasmuch as it is unnecessary to change from one type of device to another for accomplishing the desired result. It is really believed that the 25 construction, operation and advantages will be readily apparent to one skilled in the art without further explanation.

While we have shown and described a preferred embodiment of the invention, it 30 should be understood that the disclosure is merely an exemplification of the principles involved inasmuch as we reserve the right to make such changes and modifications as will increase the adaptability and widen the field 35 of utility of the device, provided such variations constitute no departure from the salient features and spirit of the invention or the scope of the claims hereunto appended.

40 Having thus described the invention, we claim:

1. In a shoe stretching device, a body member, laterally movable wing members pivoted thereon at their rear ends, a heel engaging member at the rear end of the body member and movable longitudinally thereof, and a single means for selectively swinging said wing members or moving said heel engaging member. 45
50 2. In a shoe stretching device, a body member, laterally movable wing members pivoted thereon at their rear ends, a heel engaging member at the rear end of the body member and movable longitudinally thereof, and screw means operable in one direction for swinging said wing members and operable in the other direction for moving said heel engaging member.

60 3. In a shoe stretching device, a body member, laterally movable wing members pivoted thereon, a heel engaging member at the rear end of the body member and movable longitudinally thereof, means for selectively swinging said wing members and 65 moving said heel engaging member, includ-

ing a longitudinally movable member within the body adapted to have its rear end abuttingly engage said heel engaging member, cam means at the forward end of said member engaging said wing members, and means 70 for moving said longitudinal member in one direction for moving the heel engaging member and in the opposite direction for swinging the wing members.

4. In a shoe stretching device, a body member, laterally movable wing members pivoted thereon, a heel engaging member at the rear end of the body member and movable longitudinally thereof, means for selectively swinging said wing members and 75 moving said heel engaging member, including a longitudinally movable screw having cam connection with said wing members and adapted to abuttingly engage said heel engaging member, and means threaded onto 80 the screw for moving the same in a selected direction.

5. In a shoe stretching device, a body member formed with a forwardly extending shank, wing members located at opposite 85 sides of the shank and pivoted at their rear ends to the body, said shank having a slot therein and said wing members having grooves registering with the slot, a screw 90 mounted for longitudinal sliding movement within the body and carrying a cam head engaging within said grooves, and nut means threaded onto the screw for moving the same longitudinally.

6. In a shoe stretching device, a body member formed with a forwardly extending shank, wing members located at opposite sides of the shank and pivoted at their rear ends to the body, said shank having a slot 95 therein and said wing members having grooves registering with the slot, a screw mounted for longitudinal movement within the body, a cam head engaging within said grooves and acting to prevent rotation of the screw, a gear threaded onto the screw and retained against longitudinal movement with respect to the body, an operating shaft journaled through the body at an angle to said screw and carrying an operating handle, and a gear on said shaft meshing with said first 100 named gear.

7. In a shoe stretching device, a body, means mounted thereon for engagement within the front portion of a shoe, a member mounted at the rear end of the body for engagement within the heel portion of a shoe, a plurality of guides carried by said member and slidably mounted within the body, spring means normally urging the heel engaging member toward the body, and means 115 engageable with said heel engaging member for forcing the same rearwardly with respect to the body.

8. In a shoe stretching device, a body, means mounted thereon for engagement 120

within the front portion of a shoe, a member mounted at the rear end of the body for engagement within the heel portion of a shoe, a plurality of guides carried by said member and slidably mounted within the body, spring means normally urging the heel engaging member toward the body, a screw extending longitudinally within the body and having its rear end abuttingly engageable with the heel engaging member, and gear operated nut means engaging the screw for moving the same longitudinally.

9. In a shoe stretching device, a body, means mounted thereon for engagement within the front portion of a shoe, a member mounted at the rear end of the body for engagement within the heel portion of a shoe, a plurality of guides carried by said member and slidably mounted within the body, spring means normally urging the heel engaging member toward the body, a longitudinally arranged screw within the body and shank having operative connection with said means for moving the same, said screw being engageable with said heel engaging member, and gear operated nut means for moving the screw in a selected direction.

10. In a shoe stretching device, a body member having a reduced shank at its forward portion formed with a slot, the body being formed with vertically arranged trunnion elements at opposite sides of its junction with the shank, a pair of wing members located respectively at opposite sides of the shank and formed with sockets rotatably engaged upon said trunnion elements, spring means urging said wing members together, the confronting sides of the wing members being formed with grooves having curved ends, a longitudinally movable member within the body, a cam head on said member movable along the slot and within said grooves, and means for moving said member in a selected direction.

11. In a shoe stretching device, a body formed with a reduced slotted shank at its forward portion, wing members located at opposite sides of the shank and pivoted to the body, said shank terminating at its forward end in a toe piece located forwardly

of the wing members, said wing members being formed with transverse holes, a spring extending through said holes and through the shank, anchoring elements on the ends of the spring recessed into the opposite sides of the wing members, and means for moving the wing members apart.

12. In a shoe stretching device, a body member adapted for insertion within a shoe and having a toe piece engageable within the toe portion thereof, a heel engaging member at the rear end of the body, a plurality of tubular guides carried by the heel engaging member and slideable within the rear portion of the body, coil springs located within said tubular guides, and anchor elements at the ends of each spring, the anchor element at one end being seated within the tubular guide and the one at the other end being seated within the body.

13. In a shoe stretching device, the combination of a body, laterally movable wing members, a rearwardly movable heel engaging member at the rear end of the body, a bodily shiftable member having wedging engagement with the wing members when moved in one direction and abutting engagement with the heel engaging member when moved in the opposite direction, and means for moving said shiftable member in one direction or the other for selectively moving said wing members and said heel engaging member.

14. In a shoe stretching device, the combination of a body carrying a toe piece, laterally movable wing members between the body and the toe piece, a rearwardly movable heel engaging member at the rear end of the body, means for selectively moving said wing members and said heel engaging member, said means including a longitudinally extending floating member abuttingly engageable with the heel engaging member and carrying means engageable with the wing members, and means for moving said floating member in a selected direction.

In testimony whereof we affix our signatures.

HARRY BROCK.
JACOB DAUTCH.
